UNITED STATES PATENT OFFICE

2,677,134

REMOVABLE GARMENT SECURING DEVICE

Elizabeth A. Guyton, Hempstead, N. Y.

Application November 24, 1950, Serial No. 197,459

1 Claim. (Cl. 2—265)

1

The present invention relates to wearing apparel, and has for one of its objects to provide a garment in which the buttons are easily removed.

A further object of the present invention is the provision of fastening means for a garment and one that is removable from a garment.

A still further object of the present invention is to provide a garment in which the buttons are fastened on a strip and the whole strip removable from a garment when the garment is to be cleaned.

A still further object of the present invention is the provision of a garment in which the buttons may be removed and others substituted for different styles, colors, etc.

A still further object of the present invention is the provision of a garment in which the buttons will not pull off, tear or damage the material.

A still further object of the present invention is the provision of a garment which will permit a garment to be ironed without interference from buttons.

Other and further objects of the present invention will be apparent from the following description when taken in connection with the accompanying drawing, wherein:

Figure 1 is a partial fragmentary front view of a garment with the button strip in position.

Figure 2 is a fragmentary top plan view of a button strip.

Figure 3 is a fragmentary bottom view of a button strip.

Figure 4 is a cross-sectional view of the assembled garment taken on line 4—4 of Figure 1.

It is a well known fact that in garments today there is much concern over the fastening of garments. There have been various ways tried to successfully unite the open edges of a garment which have included zippers, snap fasteners, hook fasteners, etc., but nothing so far has taken the place of buttons in uniting the edges of garments especially women's and children's blouses, and men's and boys' shirts. This has been due to many reasons, a few of which are the inexpensiveness and attractiveness of buttons, their different colors as a fashion aid and the positive opening and closing of a garment without functional difficulties such as are encountered in zippers, hook and eyes and etc.

There are still, however serious drawbacks to buttons, namely, the loss or damage to buttons and garments when being cleaned and pressed, or damage to the garments where the buttons

2

are pulled from the garment due to a tassel. Then to the trouble and time it takes to remove and replace buttons when different styles or colors are desired, or when some are lost or damaged, and the whole group must be replaced. Also the material where buttons are sewed on is weakened and torn by constant pulling and then the garment must be patched or discarded. In an effort to strengthen the portion of the garment to which buttons are sewn, reinforcing strips have been added, but this results in increased bulk, which is unsuitable for blouses and other similar garments.

My invention overcomes these difficulties by providing a removable strip of buttons which is inserted beneath the fold of a blouse, shirt or other garment.

Referring to the drawing for a more detailed description of the invention, the numeral 10 represents a strip of any suitable material to which is secured by threads 11 the attaching loop 12 of a plurality of buttons 13 and discs 14. The discs may be of any size or shape and they serve as a reinforcing member to securely hold the buttons 13 to the strip 10 and prevents the buttons from tearing loose from the strip. Any type of button may be attached to the strip such as those without holes or cloth covered buttons.

Illustrating the device in use as shown in Figure 1, the numeral 15 represents a garment having a right hand portion 16 and a left hand portion 17 which are usually the front portion of a shirt or blouse, the garment being shown fragmentary. The edge portion 18 of the right hand portion 16 is turned under and forms a flap or pocket 19 as shown in Figure 4. The edge portion 18 is provided with a plurality of buttonholes 20 that are in alignment with buttonholes 21 that are usually provided on the left hand portion 17 of a garment, button-holes 20 being in opposed relation to button-holes 21.

In using the present device the strip 10 is positioned in the flap or pocket 19 and the buttons 13 pushed through the button holes 20. The garment 15 is now equipped with fastening means and when it is desired to close the garment the buttons 13 are pushed through the button holes 21, thus closing and securing a garment as partially shown in Figure 1. It can be seen that a garment provided with extra button-holes and the strip can be buttoned and unbuttoned just as any other garment having buttons affixed. It is also to be noted that the strip is free from the garment.

If desired the strip 10 may be provided with

snap fasteners on its back face that would engage the male portion of snap fasteners on the garment, on the inner face of the pocket 19.

From the above description it can be seen that I have provided a detachable device as a closure means for shirts, blouses and the like, and one that prevents garments from being damaged by the breaking of buttons on a garment, or damage where the button is pulled off of a garment. The present device eliminates the sewing of buttons directly to a garment, provides means whereby shirts, blouses and the like may be laundered without damage to a garment.

From the foregoing description when taken in connection with the accompanying drawing, the advantages of the construction and operation will be apparent to those skilled in the art to which the invention appertains and I desire to have it understood that the device shown is merely illustrative and that such changes may be made within the scope of the claim appended.

What is claimed is:

In combination, a garment having overlapping edges and a button strip, each of said overlapping

5
10

edges doubled back upon itself, one of said doubled back edges having aligned button holes through both portions, the other of said edges having button holes only through the outermost portion, a button strip inserted between said outermost and innermost portions on said last named doubled back edge, said button strip comprising a flexible strip of suitable material having buttons of smaller diameter than said strip attached thereto on one side, and reinforcing members larger than said buttons and substantially the diameter of said strip on the opposite side of said strip, said reinforcing members being of a thickness substantially the same as the strip secured through the strip to the buttons on the other side, said buttons passing through said button holes on each of said doubled back edges.
